UNITED STATES PATENT OFFICE.

ELBERT VAUGHAN, OF PORTLAND, OREGON.

PORTABLE DRAG-SAW MACHINE.

1,165,298.

Specification of Letters Patent. Patented Dec. 21, 1915.

Application filed November 26, 1913. Serial No. 803,230.

To all whom it may concern:

Be it known that I, ELBERT VAUGHAN, a citizen of the United States, residing at Portland, in the county of Multnomah and 5 State of Oregon, have invented new and useful Improvements in Portable Drag-Saw Machines, of which the following is a specification.

The invention relates generally to drag- 10 saw machines, and particularly to a portable motor-driven machine of this type in which the parts are arranged for particular efficiency and durability.

The main object of the present invention 15 is the provision of a drag-saw machine embodying a frame having a single point of support remote from the log and spaced points of connection to the log, the saw proper being mounted in a frame operated 20 from the motor and given a tilting motion during the sawing operation to aid in clearing the saw-dust from the saw cut.

The invention in the preferred form of 25 details will be described in the following specification, reference being had particularly to the accompanying drawings, in which:—

Figure 1 is a side elevation of the improved drag-saw machine. Fig. 2 is a plan 30 of the same. Fig. 3 is a section on line 3—3 of Fig. 1. Fig. 4 is a section on line 4—4 of Fig. 2. Fig. 5 is a perspective view of the saw carrier. Fig. 6 is a side elevation of the same. Fig. 7 is an elevation of the 35 frame connector.

The improved drag-saw machine comprises a frame including main beams 1 and 2, the relatively outer or rear ends of the beams being connected by bolts 3 to a ground 40 or surface bearing block 4. The beams are connected to the block so that they are disposed in diverging relation beyond the block, the beams 1 being preferably arranged at right angles to the block and the beam 2 at an angle to the beam 1, as clearly 45 shown in the drawings. A transverse brace bar 5 is arranged intermediate the beams, and a supporting bar 6 is terminally connected to the brace bar 5 and to the beam 2, 50 said bar 6 forming a support for the motor, shown in this instance as a gasoline engine 7.

Secured upon the upper edges of the respective beams 1 and 2 in advance of the 55 ground block 4 are bearing plates 8, preferably mounted for limited adjustment lon-

gitudinally of the beams through slots 9 formed in the plates to receive the connected bolts 10. Mounted in the bearing plates 8 is the driven shaft 11 on which and between 60 the beams, and adjacent the beam 1 is fixed a sprocket wheel 12. A chain 13 connects the sprocket wheel 12 with a sprocket pinion 14 operated directly by the motor 7, whereby motion is imparted to the shaft 11 from 65 the motor. The main shaft 15 of the motor is provided with a conical extension 16 to receive the fly wheel 17, the shaft beyond the extension being threaded at 18 to receive what may be termed a cone-clutch member 70 19 on which is mounted the pinion 14, the spring 20 encircling the extension of the cone-clutch member and bearing against the pinion to normally maintain said pinion in driving coöperation with the shaft to the 75 motor, while at the same time permitting an undue strain upon the saw to cause a slip of the pinion to avoid breakage of the saw. A nut 21 threaded upon the end of the extension of the clutch member 19 holds 80 the spring to its duty.

Secured upon and arranged eccentrically with relation to the shaft 11 is a disk 22 on the periphery of which is arranged an eccentric strap 23 having an upstanding projection 24 and spaced forwardly projecting means 25 rigidly secured thereto. A guide frame of which the eccentric strap forms a part is provided including a lower guide bar 26 rigidly secured at one end between the 90 ears 25 and an upper guide bar 27 fixed at its rear end on the projection 24. The forward end of the bars 26 and 27 are secured in a bracket including an upright member 28 formed with openings 29 to receive the 95 forward ends of the guide bars, fastening means 30 being provided for securing the guide bars from the bracket. The bracket is further provided with an outwardly extending lateral arm 31 to which is secured a 100 saw guide comprising a block 32 formed with a saw receiving channel 33, the arm 31 extending outwardly beyond the block for a purpose which will later appear. The bracket is also formed with an inwardly disposed depending lug 34 designed to coöperate with the strip 35 secured upon the upper 105 end of the frame bar 1, whereby to provide for elevating the frame and holding it elevated during the transportation of the machine from one position to another. Slidably mounted upon the guide bars 26 and 27

is a saw carrier comprising a metallic plate 36 formed with a rearwardly extending lug 37 having a longitudinally arranged opening 38 therein to slidably receive the upper 5 guide bar 27, said plate being further provided adjacent its lower end with spaced lugs 39 formed with openings 40 to coöperate with the lower guide bar 26. The carrier is thus slidably held upon the frame and 10 if desired the openings in the respective lugs may be of such size as to receive elongated sleeves to slidably engage the guide bars and thus provide an extended bearing. The forward face of the plate 36 is formed adjacent 15 its upper edge with forwardly projecting lugs 41 the bottom walls of which are recessed at 42 to receive the upper edge of the saw blade 43, the lower edge of the blade being engaged by a hook 44 forming the 20 terminal of a bar 45 adapted to pass through the lug 37 with its threaded terminal engaged by a nut 46 beyond the lug. By this construction the saw blade is clamped between the hook 44 and the lugs 41, as will be 25 obvious. The carrier is also provided with a laterally extending pin 47 to receive one end of a connecting rod 48 the opposite end of which is connected to a crank 49 formed on the shaft 11, whereby in the rotation of 30 the shaft the carrier is reciprocated on the guide frame. The forward ends of the beams 1 and 2 are provided with lug engaging hooks 50 terminally mounted on pins 51 secured in the beams, brackets 52 secured to the beams in rear of the bolts 51 being formed at their forward ends with 35 openings to fit over the pins 51 beyond the hooks. The forward terminals of the hooks are formed to provide spur engaging pins 40 53, peculiarly shaped in that their relatively inner upright edges incline inwardly from a line at right angles to the main length of the hook, so that the terminal point of the spur is inwardly beyond such right angle 45 line. By this means as the hook is driven

into the log it exerts a wedging or holding action to bind the adjacent end of the beam on to the log and secure the machine to the log during the sawing operation. It will be evident that as shown in the drawings that 50 I provide the relatively inner side of each of the beams 1 and 2 with one of the log engaging hooks, so that the forward ends of both beams are anchored to the log being operated upon. 55

The operation of the device will be fully apparent from the above description taken in connection with the drawings, it being understood that the operation of the motor will reciprocate the carrier on the guide 60 frame longitudinally of the guide frame and that said guide frame will be elevated and lowered with the effect to tilt the saw at the limits of its stroke to more readily perfect a clearness. In elevating the saw for adjustment or the like the extension of the arm 65 31 of the bracket provides a convenient hand-hold.

What is claimed is:—

A saw guide and carrier for drag saw 70 machines including guide rods, a plate having rearwardly extending lugs formed with openings to slidably receive the guide rods, the face of the plate having spaced lugs to receive the upper edge of the saw and secure 75 the same between the plate and lugs, the lower edge of the plate being recessed and a rod mounted for threaded adjustment relative to the plate and terminating in a hook, said hook being operative in the recess of 80 the plate to project the bill of the hook on the same side of the plate as the lugs, the hook engaging the lower edge of the saw.

In testimony whereof I affix my signature in presence of two witnesses.

ELBERT VAUGHAN.
